(57) **CLAIM**

The ornamental design for a lamp shade accessory, as shown and described.

DESCRIPTION

FIG. 1 is a perspective view of a lamp shade accessory showing my new design attached to a base of an existing lamp shade;

FIG. 2 is top plan view thereof;

FIG. 3 is a side elevational view thereof;

FIG. 4 is a perspective view of the present invention adapted to an annular shape; and,

FIG. 5 is a perspective view of the present invention adapted to a linear shape.

The indicia or broken lines shown on the figures are for illustrative purposes only and are hereby disclaimed as forming no part of Applicant's claimed invention.

1 Claim, 3 Drawing Sheets

FIG. 1

FIG. 2

FIG. 3
